UNITED STATES PATENT OFFICE.

DONALD S. BARROWS, OF ROCHESTER, NEW YORK, ASSIGNOR TO THE SYMINGTON COMPANY, OF NEW YORK, N. Y., A CORPORATION OF MARYLAND.

DRAFT RIGGING.

Application filed March 16, 1925. Serial No. 15,858.

To all whom it may concern:

Be it known that I, DONALD S. BARROWS, a citizen of the United States, residing at Rochester, in the county of Monroe and State of New York, have invented certain new and useful Improvements in Draft Rigging; and I do hereby declare the following to be a full, clear, and exact description of the invention, such as will enable others skilled in the art to which it appertains to make and use the same.

My invention relates to draft rigging back stops such as are commonly used between the center or draft sills of railway cars for the purpose of transmitting buffing shocks from the draft rigging to the car under-frame.

The principal feature of the invention, generally considered, is to provide a back stop casting having its front or buffing wall reinforced by a transverse web, the intermediate portion of which is single and the side portions double or bifurcated, and a side wall portion of the casting extending from each of said bifurcated portions and joining with the buffing wall.

An object of the invention is the provision of a back stop casting having a reinforced front face or buffing wall and a plurality of separated side wall portions on each side thereof, a portion of the reinforcement for said front wall connecting with each of said side wall portions, whereby the metal in the casting is distributed for great strength and relatively small weight.

Another object of the invention is the provision of a back stop casting comprising a buffing wall formed with an intermediate transverse portion and angularly disposed or rearwardly flaring side portions connecting with side walls of the casting, said buffing wall being further braced and reinforced by a transverse wall comprising an intermediate, substantially horizontal portion and outwardly flaring oppositely sloping side portions, each of said side portions connecting with a portion of the side walls.

A further object of my invention is the provision of a back stop casting comprising a front or buffing wall and a rear wall, said walls being connected on each side thereof by a plurality of separated side wall portions, said side wall portions being connected and extended to the rear of the rear wall for providing increased riveting area,

and reinforcing and connecting means between said front and rear wall comprising a transverse web provided with connections to all of the side wall portions and a longitudinal web intersecting the transverse web and extending above and below the same.

With these and other objects in view, the invention further consists in the combination and arrangement of the parts as will hereinafter appear.

In the drawings illustrating my invention, the scope whereof is pointed out in the claims;

Figure 1 is a plan view showing an embodiment of my invention connected to adjacent center or draft sills.

Figure 2 is a vertical longitudinal sectional view on the line 2—2 of Figure 1, looking in the direction of the arrows.

Figure 3 is a vertical transverse sectional view taken on the line 3—3 of Figure 1 and looking in the direction of the arrows.

Referring to the drawings in which similar reference characters designate corresponding parts, my back stop casting, generally designated as 4, comprises a front or buffing wall 5, a rear wall 6, and side walls 7 and 8 extending therebetween.

The side walls 7 and 8 are each preferably formed as vertically spaced portions, each of which is connected to the draft or center sills 9 and 11 by a substantially horizontal row of rivets 12, that is, the side wall 7 is formed in two parts, an upper part 13 and a lower part 14 spaced therefrom. In the same way, the side wall 8 comprises an upper portion 15 and a lower portion 16 spaced therefrom. All of these side wall portions are connected to each other and to the front and rear wall portions 5 and 6, respectively, by a transversely extending web 17 which serves especially to brace and reinforce the buffing wall 5 and rigidly connect all parts of the back stop together.

The web 17 is preferably formed with a single substantially horizontal intermediate or central portion 18 and side portions 19, 21, 22 and 23, preferably bifurcated and flaring outwardly therefrom, as clearly illustrated in Figure 3. It will be clear from an inspection of this figure that the web portion 22 directly connects with the side wall portion 15, the web portion 23 with the side wall portion 16, the web portion 19 with the side wall portion 13, and the web portion 21

with the side wall portion 14. By reason of such a construction the casting may be made stronger without increasing the weight thereof, and the rows of rivets, for connecting it to the central or draft sills 9 and 11, may be spaced a greater distance apart, thereby increasing the strength of the connection with said sills and avoiding the application of perforations thereto which are too closely spaced.

By omitting those portions of the walls between the bifurcated sections of the transverse reinforcing web 17 and the front and rear walls of the casting, material is saved which is not necessary and would not efficiently increase the strength of the casting. This construction also facilitates the manufacture of such a casting as the same may be more readily cored.

20 The front or buffing wall of the back stop is preferably formed with a transverse intermediate or central portion 24 and rearwardly flaring or angularly disposed side portions 25 and 26 connecting said intermediate portion with the side walls 7 and 8. This construction serves to further rigidify the buffing wall and generally increase the strength without increasing the weight of the casting.

30 The buffing wall 5 at its center or intermediate portion is preferably of less depth than the over-all depth of the side walls, the side or angularly disposed portions 25 and 26 thereof, however, increasing in depth or flaring outwardly to the junction with the side walls. The buffing wall 5 may be further reinforced and braced by upper triangular webs 27 and 28 and lower triangular webs 29 and 31 between said wall and the transverse web 17.

A substantially central longitudinal and upright web 32, extending on both sides of the web 17, is also preferably provided, connecting the buffing wall 5 with the rear wall.

45 6. The buffing wall 5 is adapted for direct engagement by a movable member 33 of the draft gear, which member, in the present embodiment, is shown as a horizontal yoke. It is obvious, however, that I do not wish to be restricted to using my back stop with a yoke of such a type.

The transverse web 17 is preferably formed with a plurality of core support apertures 34 extending through the lower lateral portions 21 and 23 thereof, as illustrated most clearly in Figures 1 and 3. Additional apertures 35 may also be cored through the central or intermediate portion thereof, and the apertures in the side walls for receiving the rivets 12 may likewise be cored, if desired. The lateral portions or bifurcated sides of the transverse web 17, besides being braced and connected by the front and rear walls, may also be provided with intermediate upright transverse web portions 36, which por-

tions preferably extend outwardly almost to the outer faces of the side walls 7 and 8, respectively.

In order to provide additional riveting area without materially increasing the weight of the casting, the side walls 7 and 8 may each be extended as one piece to the rear of the rear wall 6, said extensions preferably being braced and reinforced by triangular web portions 37 and 38, extending between them and the rear wall.

For economy in design, the rear wall is preferably not quite as deep as the front or buffing wall at the central portion thereof and is flared outwardly at the side portions to approximately the same depth as the side walls where it merges therewith.

By virtue of the foregoing, I have provided a draft rigging back stop which is relatively light in weight and yet strong enough for the service desired. By providing a transverse reinforcing web which is single at its intermediate or central portion and provided with outwardly flaring or bifurcated side portions, each of which portions connects with a section of the side walls, I minimize the weight of the casting while retaining adequate strength therein. That is, the central portion of the transverse web is sufficiently strong because of the longitudinal upright web 32 connecting front and rear walls. The double side portions of the web, by the omission of wall portions between said double portions, saves material and permits spacing the rows of connecting rivets a maximum distance apart, thereby providing a very rigid connection to the center or draft sills.

By extending the side walls beyond the rear wall of the casting, a substantial increase in riveting area is provided without a corresponding increase in weight of the casting.

Having now described my invention, I claim:

1. A draft rigging back stop comprising side walls adapted to be secured to spaced car sills, a forward end wall united to said side walls and adapted to serve as an abutment for a movable part of a draft rigging, and longitudinally disposed transversely diverging webs uniting the side walls and forming a V-shaped section for reinforcing said forward end wall.

2. A draft rigging back stop comprising side walls adapted to be secured to spaced car sills, a forward end wall united to said side walls by rearwardly flaring wing portions and adapted to serve as an abutment for a movable part of a draft rigging, and longitudinally disposed transversely diverging webs uniting the side walls and forming a V-shaped section for reinforcing said forward end wall.

3. A draft rigging back stop comprising

- side walls adapted to be secured to spaced car sills, a forward end wall united to said side walls and adapted to serve as an abutment for a movable part of a draft rigging, and longitudinally disposed transversely diverging webs uniting the side walls and forming a section consisting of an intermediate substantially horizontal web and outer portions sloping transversely therefrom for reinforcing said forward end wall. 5
4. A draft rigging back stop comprising side walls adapted to be secured to spaced car sills, a forward end wall united to said side walls by rearwardly flaring wing portions and adapted to serve as an abutment for a movable part of a draft rigging, and longitudinally disposed transversely diverging webs uniting the side walls and forming a section consisting of an intermediate substantially horizontal web and outer portions sloping transversely therefrom for reinforcing said forward end wall. 10
5. A draft rigging back stop comprising a plurality of spaced side walls on each side of the longitudinal center line thereof, a forward end wall united to all of said side walls and adapted to serve as an abutment for a movable part of a draft rigging, and longitudinally extending outwardly flaring webs uniting the side walls with the front wall and with each other. 25
6. A draft rigging back stop comprising a plurality of spaced side walls on each side of the longitudinal center line thereof, a forward end wall increasing in depth from its intermediate portion to its end portions where it is united to all of said side walls and adapted to serve as an abutment for a movable part of a draft rigging, and longitudinally extending outwardly flaring webs uniting the side walls with the front wall and with each other. 30
7. A draft rigging back stop comprising a plurality of spaced side walls on each side of the longitudinal center line thereof, a forward end wall provided with angularly disposed wing portions united to all of said side walls and adapted to serve as an abutment for a movable part of a draft rigging, and longitudinally extending outwardly flaring webs uniting the side walls with the front wall and with each other. 45
8. A draft rigging back stop comprising a plurality of spaced side walls on each side of the longitudinal center line thereof, a forward end wall provided with angularly disposed wing portions increasing in width towards the sides of the back stop where they are united to all of said side walls and adapted to serve as an abutment for a movable part of a draft rigging, and longitudinally extending outwardly flaring webs uniting the side walls with the front wall and with each other. 60
9. A draft rigging back stop comprising a plurality of spaced side walls on each side of the longitudinal center line thereof, a forward end wall united to all of said side walls and adapted to serve as an abutment for a movable part of a draft rigging, and longitudinally extending outwardly flaring webs connecting the side walls with the front wall and with each other. 65
10. A draft rigging back stop comprising side walls adapted for connection to car sills, front and rear walls extending therebetween, all of said walls being united by a transverse web consisting of an intermediate substantially horizontal portion, and bifurcated side portions, each of said side portions connecting with a side wall. 70
11. A draft rigging back stop comprising side walls adapted for connection to car sills, front and rear walls extending therebetween, all of said walls being united by a transverse web consisting of an intermediate substantially horizontal portion, and bifurcated side portions, each of said side portions connecting with a side wall, and a substantially vertical longitudinal web connecting said front, rear and transverse web portions. 75
12. A draft rigging back stop comprising side walls adapted for connection to car sills, front and rear walls extending therebetween, all of said walls being united by a transverse web consisting of an intermediate substantially horizontal portion and bifurcated side portions, each of said side portions flaring away from the plane of the intermediate portion and connecting with a side wall. 80
13. A draft rigging back stop comprising front and rear end walls, side walls each comprising a plurality of separated portions joining said end walls, all of said walls being braced and joined by a transverse web member, said member being single at the intermediate portion thereof and bifurcated at the sides thereof, each of said bifurcated portions extending outwardly and connected with a portion of the side walls. 85
14. A draft rigging back stop comprising front and rear end walls, side walls each comprising a plurality of separated portions joining said end walls, all of said walls being braced and joined by a transverse web member, said member being single at the intermediate portion thereof and bifurcated at the sides thereof, each of said bifurcated portions extending outwardly and connected with a portion of the side walls, and an upright substantially longitudinal web connecting said front and rear walls. 90
15. A draft rigging back stop comprising front and rear end walls, side walls each comprising a plurality of separated portions joining said end walls, all of said walls being braced and joined by a transverse web member, said member being single at the intermediate portion thereof and bifurcated at the sides thereof, each of said bifurcated portions extending outwardly and connected with a portion of the side walls, and an upright substantially longitudinal web connecting said front and rear walls. 95

member, said member being single at the intermediate portion thereof and bifurcated at the sides thereof, each of said bifurcated portions extending outwardly and connected with a portion of the side walls, said side walls being provided with extensions beyond the rear wall, and triangular bracing webs between the end wall and said extensions.

16. A draft rigging back stop comprising side walls adapted to be secured to car sills, a front wall comprising a transverse portion and rearwardly flaring end portions united with said side walls, and a webbed member comprising a central single portion and outwardly flaring side portions connected with and bracing said end and side walls.

17. A draft rigging back stop comprising side walls adapted to be secured to car sills, a front wall comprising a transverse portion and rearwardly flaring end portions

united with said side walls, a webbed member comprising a central single portion and outwardly flaring side portions connected with and bracing said end and side walls, and triangular bracing webs between said front wall and webbed member. 25

18. A draft rigging back stop comprising side walls adapted to be secured to car sills, a front wall comprising a transverse portion 30 and rearwardly flaring end portions united with said side walls, and a webbed member comprising a central single portion and outwardly flaring side portions connected with and bracing said end and side walls, the 35 over-all depth of said end wall at intermediate portions thereof being less than that of said side walls but approaching that of said side walls at the ends thereof.

In testimony whereof I affix my signature.

DONALD S. BARROWS.
